UNITED STATES PATENT OFFICE.

EUGENE W. APPLEGATE, OF CHICAGO, ILLINOIS, ASSIGNOR, BY MESNE ASSIGNMENTS, TO AUGUST HEUER, JR., AND CHARLES L. DAVIS, OF SAME PLACE.

MECHANICAL MUSICAL INSTRUMENT.

SPECIFICATION forming part of Letters Patent No. 675,551, dated June 4, 1901.

Application filed May 11, 1900. Serial No. 16,815. (No model.)

To all whom it may concern:

Be it known that I, EUGENE W. APPLEGATE, a citizen of the United States, residing at Chicago, in the county of Cook and State of Illinois, have invented a certain new and useful Improvement in Mechanical Musical Instruments, (Case No. 3,) of which the following is a full, clear, concise, and exact description, reference being had to the accompanying drawings, forming a part of this specification.

My invention relates to mechanical piano-players which can be operated so as to strike the keys of pianos or like instruments, and thereby cause the mechanical playing of the same.

Mechanical piano-players of the kind to which I refer are provided with a series of striking-fingers which are arranged so as to come in position over the keys of a piano-keyboard when the player is set against the front of the piano and which are mounted so that they can be independently depressed, so as to strike their allotted keys. The depression of the various keys at proper times to play various compositions is caused by suitable pneumatic devices, which are in turn operated by the admission of air through ports formed in a long board, commonly called a "tracker-board." The admission of air to these ports is controlled by sheets or strips of paper, which are drawn one by one across the tracker-board and which are provided with apertures so situated as to admit air into the proper ports for actuating the piano-keys, so as to play different musical compositions.

The sheets or strips of music for mechanical piano-players, properly perforated to control the admission of air into the ports of the tracker-board, are carried by spools or bobbins, upon which they are wound for shipment and storage. In the operation of the player these sheets or strips are drawn successively across the tracker-board by being slowly unwound from their spools and wound upon a suitable reel or roll, which may be called a "storage" reel or roll. In the practice of the present day after a sheet or strip of music has thus been transferred from its spool to the storage-reel it is then and there

immediately retransferred to its spool by rotating the latter in a reverse direction, so as to rewind the sheet or strip upon it. As a result the persons listening to the music must wait a few minutes between each piece for the operator to rewind the played strip before he can insert and connect a spool carrying a fresh strip.

It is a primary object of my invention to avoid the inconvenience and loss of time incident to thus rewinding each played strip before introducing a new one.

In the arrangement hereinafter shown for carrying out my invention I provide a second storage reel or roll, upon which a second sheet or strip of music can be wound immediately after the first one has been drawn across the tracker-board, and I arrange for the rewinding or rerolling of the first-played strip upon its reel simultaneously with the drawing of the second strip across the board. In this way as each strip is drawn across the tracker-board the previously-played strip is being wound upon its spool. Consequently the compositions can be played without any intervening delays. In the arrangement shown the two storage-reels upon which the successive music-strips are wound are made interchangeable in position in the rear of the tracker-board, so that the strips can all have the same path of travel in passing over the tracker-board. I also arrange for repeating any desired composition.

My invention also contemplates other matters hereinafter set forth.

In the accompanying drawings, Figure 1 is a plan of a device of the class specified embodying my invention. Figs. 2 and 3 are end views of the same, Fig. 2 looking at the right-hand end of Fig. 1 and Fig. 3 at the left-hand end of the same. Fig. 4 is a plan of a portion of the device on a larger scale, and Figs. 5 to 8 are views of details of construction.

In the drawings the tracker-board of the piano-player is illustrated at A, Fig. 1, and is provided with transversely-extending apertures 11. This tracker-board, it will be understood, is suitably mounted in the piano-

player and has its apertures connected with pneumatic apparatus therein in the ordinary or any suitable way. As such player and its mechanism form no part of my present invention, neither one has been shown herein.

The drawings show a sheet or strip B of music being moved across the tracker-board A, so as to control the admission of air into the tracker-board ports. This advancement of the music is caused by driving or rotating a storage-reel C, so as to wind the strip upon it and unwind the same from the spool or bobbin D, which normally carries it. The drawings, Fig. 2, also show another sheet or strip of music B', which is understood to have been played previously to the playing of the strip B. The strip B' is shown as being unwound from a second storage-reel E and wound upon a spool or bobbin F. The spool F is the one normally carrying this strip B', and the storage-reel E is the reel upon which this strip was wound in order to draw it across the tracker-board. The rewinding of the strip B' is accomplished by rotating its spool F. In this way it will be seen that a played strip can be wound simultaneously with the playing of a new one and the delay and inconvenience incident to the separate rewinding of such played strip can be avoided.

The storage-reels C and E are desirably mounted so that they can be interchanged in position in the rear of the tracker-board, a simple arrangement being to mount them upon a swinging frame consisting of a rotary disk 2 and a swinging arm 3. A holder for the spool or bobbin D, carrying the strip B of music being played, is arranged in front of the tracker-board, so as to coöperate with whichever one of the storage-reels C and E is in foremost or drawing position. The holder shown consists of a couple of arms 4 4, provided with a fixed and a spring socket to receive the ends of the spool-spindle. A holder for the spool or bobbin F, carrying the strip B' of music being rewound, is arranged in position to coöperate with the storage-reel E after such reel has been swung out of receiving position and replaced by the reel C. A simple arrangement of holder is to extend a pair of arms 5 5 upwardly and rearwardly from the framework 6 and to provide them, respectively, with a fixed and a spring socket for receiving the opposite ends of the spool-spindle. By such arrangement it will be seen that after the spool D, carrying a sheet or strip of music B to be played, is fitted into the sockets provided by the arms 4 4 its loose end can be attached to the reel C, as by the pin c, and then this reel C can be turned so as to draw the strip B properly across the tracker-board. It will also be seen that a spool F of a previously-played strip B' can be fitted into the holder provided by the arms 5 5, and this spool F can be turned so as to withdraw the strip B' from the reel E. This rotation of the spool F to rewind or reroll the previously-played strip B' can and preferably does occur

simultaneously with the driving of the reel C, receiving the played strip B. In operating the device, therefore, a spool or bobbin D is fitted into the sockets of the arms 4 4, and the end of the music-strip B, carried by such bobbin, is attached to the reel C. This reel is then rotated, so as to draw the strip B properly across the tracker-board. When this has been done, the spool D is removed from the sockets of the arms 4 4 and placed in the sockets at the ends of the arms 5 5, and the swinging frame carrying the reels C and E is swung so as to bring the reel C into coöperating position with this spool when it is supported by the arms 5 5 and also to bring the storage-reel E in position immediately in the rear of the tracker-board A. A spool carrying a second strip of music is then inserted in the sockets of the arms 4 4 and its end connected with the reel E. The reel E and the first-mentioned spool, which is now supported by the arms 5 5, are then driven so as to simultaneously draw the second strip across the tracker-board and at the same time rewind the first strip upon its spool D. When the second strip has been drawn across the tracker-board and the first one has been rewound, the spool of the former is placed in the sockets at the ends of the arms 5 5 and the swinging frame carrying the reels C and E are interchanged in position. In the drawings, especially in Figs. 2 and 3, the strip B' can be considered as representing such a second strip and the spool F the spool which carried it and which has been transferred from the sockets of the arms 4 4 to the position shown at the ends of the arms 5 5. The end of the strip B' is then attached to its spool F. A spool carrying the third strip is next fastened in the sockets at the ends of the arms 4 4, and the end of this strip is attached to the reel C, which is understood to be now emptied of the first strip by the rewinding of such strip upon its spool. In the drawings the spool D represents such a third spool and the strip B a fresh strip carried by the same. The spool F and reel C are then driven so as to rewind the second strip B' and to draw the third strip B across the tracker-board. This operation is continued as long as desired, the spool of each strip after the playing of the strip being transferred to the rear of the device, the storage-reels being shifted in position and a fresh strip being inserted in the sockets in front of the tracker-board and attached to the empty storage-reel.

As an arrangement for driving whichever one of the storage-reels is in receiving position I have shown, Fig. 1, the ends of the storage-reels C and E provided with gear-wheels 7 and 8, respectively, and have also shown the driving-pinion 9 mounted so as to mesh with and drive either one of the gears 7 and 8, according as one or the other of the reels C and E is in forward position. The pinion 9 is carried by a shaft 10, and this shaft is driven by a belt 11, passing over the wheel 12 on the

shaft 10. The belt 11 is understood to be driven by any suitable power mechanism, usually by an air-motor in the case of mechanical piano-players.

5 In order to allow the shaft 10 to remain stationary, as when it is desired to place the spool carrying a fresh strip in position, and fit this strip over the tracker-board, I arrange the wheel 12 upon a spline 13, Fig. 8, fitted to the 10 shaft 10, so that when the wheel 12 is moved sufficiently to the right it engages the spline 13, and thereby rotates the shaft 10, whereas when it is moved to the left it will become disengaged from the spline and will rotate 15 freely about the shaft 10 without rotating the latter. I provide a lever 14 for moving the driving-wheel 12 upon the shaft 10.

As an arrangement for simultaneously driving the spool of the previously-played strip 20 when the same is supported in the sockets at the ends of the arms 5 5 I arrange (see Fig. 1) a pulley 15 on the end of one of the sockets and extend a belt 16 over this pulley 15 and also over the pulley 17, loose on the shaft 25 10. I also arrange a pin 18 upon the wheel 17 and also provide a pin 19 on the hub of the wheel 12, adapted to engage the pin 18 when said wheel 12 is moved sufficiently to the right, Fig. 4. In this way when the driving-wheel 30 is moved sufficiently to the right to engage the spline 13, and thereby drive the shaft 10, the driven or receiving storage-reel will be properly driven to cause the playing of the strip of music, and by moving the same wheel 35 12 still farther to the right, so as to cause it to engage the wheel 17, a spool supported by the arms 5 5 will be rotated, so as to simultaneously rewind the previously-played strip upon it.

40 The mechanism for rewinding the previously-played strip—that is to say, the pulleys 15 and 17 and belt 16 in this case—is desirably so arranged as to cause the rewinding to occur at a rate of speed more rapid than that at which the playing-strip is advanced over the tracker-board. In the arrangement shown the pulley 17 is smaller than the pulley 15. By such arrangement a previously-played strip longer than the one being played 45 50 can be rerolled before or as soon as the playing of the latter is completed. It will be understood, of course, that as soon as a strip has become fully rewound its end will become detached from the reel E by sliding off from the small hook with which said reel is provided in the way now common in the operation of instruments of this kind.

In case the two strips are of substantially the same length or of any such other relative 55 60 lengths as to cause the previously-played strip to become rerolled before the playing of the other strip is completed the rerolling mechanism is disconnected, and thereby stopped, without interfering with the playing.

65 I also desirably arrange so that a piece of music once played can be played again. To such end I provide means for rotating the

spool carrying the playing-strip, so that this strip can be drawn backward and then again drawn forward over the tracker-board. The 70 arrangement shown for this purpose comprises a pulley-wheel 20, loose on the shaft 10, and another pulley 21 on the spindle 22, forming an extension of one of the sockets for supporting the spool carrying the playing-strip. A belt 23 is extended over the pulley-wheels 20 and 21. The wheel 20 is provided with a pin 24, adapted to engage a pin 25 on the side of the driving-wheel 12. By such arrangement when the wheel 12 is moved 80 sufficiently to the left to cause the pins 24 and 25 to become engaged the wheel 20 will be driven and the spool D will be rotated in a backward direction. This rotation can be continued until the strip of music is rolled 85 upon it, at which time the backward rotation will be stopped. The driving-wheel 12 will then be moved to the right to an extent to cause it to engage the spline 13 on the shaft 10, whereby said shaft will be again driven 90 in a direction to draw the strip of music over the tracker-board.

I desirably provide a standard H below the lever 14 for moving the driving-wheel 12 and form at the end of this standard notches h, 95 adapted to engage a catch on the lever, and thereby hold the latter in proper adjusted positions. These notches h are provided with suitable words showing the operation of the device when the lever is adjusted to coincide 100 with them. These words are "Reroll," "Play," "Idle," and "Release." When the lever is adjusted to the word "Reroll," the device will both draw the playing-strip across the tracker-board and reroll a previously-played strip. 105 When adjusted to the word "Play," it will draw a strip across the board without operating the rerolling mechanism. When adjusted to the word "Idle," the driving mechanism will be disconnected from both the 110 playing and the rerolling mechanisms and the device will not operate. When adjusted to the word "Release," the spool carrying the playing-strip will be rotated in a reverse direction, so as to rewind the playing-strip on 115 its spool, and thereby allow its repetition.

I desirably provide means whereby the storage-reel can be automatically disconnected from its driving connection. This is conveniently done by actuating the swinging frame 120 carrying the storage-reels so as to elevate its forward portion, and thereby throw the one of the gears 7 and 8 in mesh with the pinion 9 out of mesh therewith. This is desirably accomplished by the lever 14 in its movement from the notch marked "Idle" to the one marked "Release." In the arrangement shown for this purpose the lever 14 is provided with a long finger 27, which is extended downwardly therefrom, and this finger 27 125 13 acts when the lever is swung sidewise upon a lug or projection 28 on a rod 29, extended horizontally across the machine, as shown in Fig. 1. The end of the rod 29 is connected

with one arm of a bell-crank 30, and the other arm of this bell-crank is arranged below a vertically-movable slide 31, so that when the rod 29 is actuated the bell-crank 30 will elevate the slide 31. The upper end of the slide 31 is provided with a tooth or pin 32, Figs. 2 and 5, which is adapted to fit into notches 33 in the disk 2. By such arrangement the elevation of the slide 31 will rotate the disk 2 to a small extent, and thereby throw the one of the gear-wheels 7 and 8 meshing with the pinion 9 out of mesh therewith. The slide 31 is held normally in a lowered condition by a spring 33, Fig. 2. It will be understood that this release or disconnection of the active storage-reel occurs immediately upon the movement of the lever 14 to its extreme right or the release position, and after this is done the lever is returned immediately to the idle position, so that the mechanism for driving the spool D in a reverse direction does not have time to operate. If it is desired to rotate the spool D backward, the lever 14 is held at the release position as sufficient length of time to accomplish that end.

With reference to the structure of the device it will be understood that the arms 4 and 5 are extended from suitable frame-pieces 6 6, arranged on opposite sides of the swinging frame carrying the storage-reels, and that these frame-pieces 6 6 serve as supports for the axis or shaft 35 35 of the swinging frame. It will also be understood that the frame-pieces 6 6 are mounted upon a suitable support 36, which is arranged and secured upon the top of the piano-player with which the device is associated.

From the foregoing it will be seen that my invention provides for the rerolling of a sheet of music immediately after it has been played, for the playing of the music after the rerolling of the previously-played strip has been completed, and for the repeating of any strip desired.

45 5. What I claim as my invention is—

1. The combination with the tracker-board; of means for drawing a music-strip across the same, separate means for rewinding a previously-played strip, and mechanism for simultaneously operating both the drawing means and the rewinding means.

2. The combination with the tracker-board, of a couple of storage-reels, either one of which can receive a strip of music from the tracker-board; means for driving whichever one of said reels is receiving the strip; and means for rotating a spool of a previously-played strip, simultaneously with the driving of the driven storage-reel.

60 3. The combination with the tracker-board and means for holding the spool of the music-strip to be drawn across the board; of a couple of storage-reels; means whereby the same can be interchanged in position to cooperate with the spool of the strip being played; means for driving whichever one of said reels

is in drawing position; a support for a spool of a previously-played strip, arranged to allow said spool to coöperate with the undriven reel; and means for driving said spool. 70

4. The combination with the tracker-board, and means for holding a music-carrying spool detachably in front of the same; a swinging frame carrying a couple of reels, and adapted to allow either one of said reels to be placed 75 in the rear of the tracker-board so as to coöperate with the spool in front of the same to draw a strip across such board; means for driving whichever reel on said frame is in position to coöperate with said spool; and means 80 for simultaneously driving a second spool so as to rewind a previously-played strip.

5. The combination with the tracker-board; of means for drawing a sheet or strip of music across the same; and means for simultaneously rewinding a previously-played strip at a greater rate of speed than that at which the first-mentioned strip is drawn across the tracker-board. 85

6. The combination with the tracker-board, 90 of a support for a spool on one side of the same; a swinging frame carrying a couple of storage-reels, said frame being so mounted that by swinging it the reels can be interchanged in position on the side of the tracker-board opposite the spool; gear-wheels on said reels; a driving-pinion adapted to mesh with the gear on whichever one of the reels is in drawing position; a spindle carrying a socket 95 adapted to engage a spool of a previously-played strip; and power-transmitting connection for driving both said pinion and said spindle. 100

7. The combination with the tracker-board, and means for holding a music-spool; of a 105 couple of storage-reels; and means for interchangeably supporting said reels in position on the side of the tracker-board opposite the holder for the spool.

8. The combination with the tracker-board, 110 and sockets for holding a spool for music; of a couple of storage-reels; a rotatable frame carrying said reels; gear-wheels on the reels; a pinion adapted to mesh with either one or the other of the gear-wheels according to the 115 position of the rotatable frame; means for driving said pinion; a couple of sockets adapted and positioned for holding a spool to coöperate with the inactive storage-reel; and power-transmitting connection between one 120 of the sockets for the spool of a previously-played strip and said pinion.

9. The combination with the tracker-board, and means for drawing a strip of music across the same; of separate means for rewinding a 125 previously-played strip; and means for driving the drawing means, and also for driving the rewinding means at any time during the driving of the drawing device.

10. The combination with the tracker-board, 130 and means for drawing a strip of music across the same; of separate means for rewinding a

previously-played strip; means for simultaneously driving both the drawing and rewinding means; and means for stopping the operation of the rewinding means, without stopping the drawing means.

11. The combination with two storage-reels; of a rotatable frame carrying the same; means for driving either one of the storage-reels according as one or the other is in driving position; a holder for the spool of a previously-played strip, said holder being arranged in position to coöperate with the un-driven storage-reel; means for actuating said holder so as to drive said spool; and mechanism for connecting and disconnecting said driving means at will without disconnecting the means for driving the driven storage-reel.

12. The combination with two storage-reels; of a rotatable frame carrying the same; gear-wheels on said reels; a rotary shaft carrying a pinion adapted to gear with one or the other of the gears on said reels, according to the reel which is in driving position; sockets for the spool of the previously-played strip of music, one of said sockets being provided with a pulley; another pulley on the shaft carrying said pinion; a belt extending over said pulleys; and a clutch for connecting and disconnecting the pulley on said shaft with the same.

13. The combination with the tracker-board, and means for drawing a strip of music across the same; of means for rereeling a previously-played strip; means for reversing and rewinding the playing-strip; and means for driving either the rereeling or rewinding means at will.

14. The combination with the tracker-board and a holder for a music-strip spool; of a couple of storage-reels; means whereby said reels can be interchanged in position on the side of the tracker-board opposite the holder for the playing music-strip; means for driving whichever one of said reels is in position to coöperate with said holder; a holder for the spool of a previously-played strip, said last-mentioned holder being adapted and positioned to coöperate with the un-driven storage-reel; means for driving the spool of the playing-strip in a reverse direction; means for driving the spool of the previously-played strip; mechanism for actuating the last-mentioned driving means simultaneously with the driving of the driven storage-reel; and mechanism for disconnecting the means for driving the driven storage-reel when the means for reversing the spool of the playing-strip is actuated.

15. The combination with the tracker-board; of a couple of storage-reels; a rotatable frame carrying the same; gearing for driving either one of said reels according as one or the other is in driving position; a rotary driving-shaft for driving said gearing; a socket for holding the spool of the previously-played strip; power-transmitting connection for driving

said socket-spindle from said rotary shaft; a spindle carrying a socket for the spool of the playing-strip; power-transmitting connection for driving said spindle from said rotary driving-shaft; and a clutch member on said shaft, said clutch being adapted to engage and drive the rotary shaft, and also to allow the same to remain stationary, and also being adapted to engage either the power-transmitting connection for driving the spool of the previously-played strip, or the power-transmitting connection for reversing the playing-strip, the engagement of the transmitting connection for driving the previously-played strip occurring at a time when the clutch is in engagement with the shaft for driving the driven storage-reel.

16. The combination with the rotatable frame carrying the reels; of power-transmitting connection for driving whichever one of said reels is in driving position; means for starting and stopping said power-transmitting connection; and means for automatically disconnecting the same.

17. The combination with the rotatable frame carrying the storage-reels; of a slide having a pin adapted to engage notches on one side of the frame; a bell-crank for operating said slide; a rod for operating the bell-crank; and a swinging lever having a finger adapted to engage a lug on said rod.

18. The combination with the tracker-board, and the sockets for holding the spool of the playing-strip; of a rotatable frame carrying a couple of storage-reels; gear-wheels on said reels; a driving-shaft carrying a pinion adapted to engage with either of said gear-wheels according as one or the other of the storage-reels is in driving position; a pair of sockets for the spool of a previously-played strip; power-transmitting connection between the spindle of one of said sockets and said driving-shaft; power-transmitting connection between said driving-shaft and one of the spindles of the spool of the playing-strip for driving said spool; a driving-wheel normally loose on its shaft, and adapted to engage the same when shifted longitudinally of the shaft; a clutch on said driving-wheel adapted to engage the power-transmitting connection for driving the spool of the previously-played strip, said engagement occurring at a time when said driving-wheel is in engagement with the driving-shaft, and another clutch member on said driving-wheel adapted to engage the power-transmitting connection for reversing the spool of the playing-strip, said engagement occurring at a time when said driving-wheel is disconnected from the driving-shaft, substantially as described.

19. The combination with the tracker-board, of means for drawing a music-strip across the same, and means for rewinding a previously-played strip without drawing such strip across the tracker-board.

20. The combination with a tracker-board,

of a pair of spools arranged one in front and the other in the rear of the tracker-board, a second pair of spools one of which is arranged near the rear spool of the other pair, means for interchangeably supporting the rear spool of the first-mentioned pair and the spool of the other pair nearest thereto, and means for simultaneously driving the rear spool of the

first-mentioned pair and the spool of the other pair farthest therefrom.

In witness whereof I hereunto subscribe my name this 17th day of April, A. D. 1900.

EUGENE W. APPLEGATE.
